UNITED STATES PATENT OFFICE.

JOSEPH D. STONE, OF ARLINGTON, NEW JERSEY, ASSIGNOR TO WORTHINGTON PUMP
AND MACHINERY CORPORATION, A CORPORATION OF VIRGINIA.

CONDENSER.

1,424,786.

Specification of Letters Patent. Patented Aug. 8, 1922.

Application filed September 6, 1917. Serial No. 189,932.

To all whom it may concern:

Be it known that I, JOSEPH D. STONE, a citizen of the United States, and a resident of Arlington, county of Hudson, and State 5 of New Jersey, have invented certain new and useful Improvements in Condensers, of which the following is a specification.

My invention relates to condensers made use of for condensing steam from the 10 exhaust of steam utilizing devices, such as engines.

Turbine steam engines are commonly set on foundations provided with large cavities or recesses for the accommodation of condensers comprising shells, water boxes, etc., made entirely of metal, into which the exhaust steam is discharged and there condensed. With such arrangement the concrete foundation is weakened by the 15 presence of the large recesses required, which must exceed the dimension of the condenser in order to provide access to the condenser set therein, and enormous masses of metal are required for the construction of the 20 condensers for large power units; great difficulty is found, also, in preventing injury to the turbine or rupture of the connection between the turbine and the condenser owing to the expansion of the condenser shell.

According to my invention the concrete 30 of the foundation is made to serve also as the walls of the condenser, thereby greatly reducing the amount of metal required for the condenser, producing a very strong and 35 substantial foundation and cutting down the outside dimension of the foundation by eliminating the need for clearance space between the condenser and the foundation, which space, according to my invention, is prefer- 40 ably filled with concrete.

An object of the invention is the production of a condenser structure having the 45 advantageous features above referred to, and with the foregoing and related objects in view, my invention consists in the constructions, improvements, parts and combinations herein set forth and claimed.

For the purpose of affording an understanding of my invention, I have illustrated 50 in the accompanying drawing, forming a part of this specification, one form in which my invention may be embodied.

In the said drawing, Figure 1 is a plan 55 view of a combined foundation and con- denser. Figure 2 is a side view thereof with

an engine and generator in place thereon. Figure 3 is a transverse cross-sectional view, and Figure 4 is a longitudinal cross-sectional view of the construction shown in Figure 1.

Reference numeral 10 designates the concrete, which is preferably made as dense and coherent as possible and may be suitably reinforced if desired, and which serves to form the enclosure for the condenser as well as the foundation for the engine 11, here 60 shown as a turbine engine, and also serves as a foundation, in the construction shown, for the generator 12 directly connected to the turbine. The I-beams 13, embedded in the upper portion of the concrete, serve as 65 foundation sills for the engine, and in the form shown the exhaust 14 from the engine is received directly in the steam inlet opening 15 formed in the top of the concrete structure. Means permitting relative ex- 70 pansion and contraction of the exhaust connection are preferably utilized for making a steam-tight connection between the exhaust pipe 14 and the concrete structure, and in the form shown a plate 16, preferably of 75 metal, is embedded at its edges in the concrete and is secured to the exhaust opening 14, leaving an annular space 17^a closed only by the plate 16 and permitting such slight 80 relative movements of the parts as may re- 85 sult from expansion and contraction of the exhaust connection, and at the same time affording a tight joint. The inlet opening 15 leads to the hollow interior of the concrete structure, which serves as the condensation 90 chamber. Its walls are preferably cored out in the concrete, but they may be lined, as with sheet metal, for example, if desired, which may serve as the form or core in 95 putting the concrete in place. At the ends of the preferably substantially cylindrical hollow space within the concrete structure are rings 17 and 17', which may be of cast iron and may be in one piece or sectional. These are embedded in the concrete as the 100 latter is put in place, and are arranged op- 105 posite and in substantial alignment with one another. The space between the rings serves to provide the condensation chamber for the condenser, and when continuous rings are provided the rings themselves may form the peripheral walls for the water boxes. The members 17, 17' may not be complete rings at all parts, if desired. Con- siderable metal may be saved in this way. 110

For example, the peripheral walls of the water box may be made up for the most part of concrete with four or more metallic strips to bridge over between separate narrow rings 5 to which the tube plates and water box heads are respectively connected.

Tube plates 18 and 18' are secured within the rings 17, 17', and are preferably seated against flanges 19, 19', so that they may be 10 introduced through the open ends of the rings. The tubes 20 are secured in the tube plates 18, 18' in any manner, as by screw-bushings with packing, or by expansion or 15 in other ways. The tube plates 18, 18' are preferably braced, and when they are divided into quarters, as is preferably the case with plates of a large size, the braces may also cover the joints between the sections. In the form shown horizontal braces 21 are 20 provided extending across the middle of the tube plates and are supported at their ends in inward extensions of the rings 17, 17', and vertical braces 22, 22 are provided and are secured to the tube plates along the vertical section line between the separate parts 25 thereof, and are also preferably secured at their ends to the inward extensions of the rings 17, 17'.

The tubes 20 are preferably supported between their ends to prevent sagging. In the form shown there are two perforated supporting plates 23, 23 held by cross-braces 24, 24 between which are interposed longitudinal members for holding the tube plates 30 outward against air pressure, pipes 25, 25 being preferably made use of for this purpose. In the form shown the braces 24, 24 are secured at one end to plates 26, 26 embedded in the concrete and having the form 35 of short channel bars, and their opposite ends are secured to an elongated channel bar 27 embedded in the concrete on the opposite side.

The tubes 20 in the condenser casing may 40 be arranged in any preferred way. I prefer to arrange the tubes in the upper part of the condenser casing in vertical sets with channels 28, 28 at intervals between them, and the tubes in the lower part thereof are 45 shown as having short downwardly leading openings 29, 29 between them to permit proper circulation of the steam.

In the form shown there are three openings 50 to the interior of the casing of the condenser, an opening 30 for free steam exhaust, which may be equipped with the usual valve and may be provided with a collar 31 embedded in the concrete for making tight 55 connections, the opening 32 leading to the well 33 in which the water obtained from steam condensation is collected and from 60 which it may be drawn off, as by a pump, and the air exhaust opening 34, also equipped with a collar as in the case of the 65 other two openings. A baffle plate 35, ar-

ranged over the mouth of the opening 34 and preferably inclined downward therefrom and received between the tubes, is provided to prevent withdrawal of the steam through the air exhaust opening 34. Any 70 or all of the openings 30, 32 and 34 may be sufficiently large to serve as manhole openings whereby access may be had to the interior of the casing when necessary.

The water boxes 36 and 36', as already 75 stated, preferably occupy the space within the rings 17, 17'. They are provided with heads 37, 37' having manholes provided with cover plates 38, 38' to permit access to the tube plates. Braces are preferably provided 80 within the water boxes, and when the heads and tube sheets are in quadrant form, these braces, like the braces within the condensation chamber, may be arranged centrally, vertically and horizontally so as to cover 85 and close the joints between the sections. These braces preferably extend from the tube sheets to the water box heads. In the form shown the horizontal brace 39 is solid so as to prevent the passage of water, while the corresponding brace 39' in the water box 36' is provided with water circulation 90 openings, as are also the vertical braces 40 and 40' and 41 and 41'. The water circulation may be varied, as desired, but in the 95 form shown a two pass circulation is used, the water being admitted into the water box 36 preferably through the lower opening 42, whence it passes through the tubes 20 to the lower part of the water box 36', thence upwardly through the plate or brace 39' and back through the upper tubes to the upper portion of the water box 36, whence it is discharged through the outlet opening 43. The water box 36, to the sides of which the 100 ingress and egress water pipes are connected, is preferably somewhat deeper than the water box 36' to permit the formation of lateral openings therein of sufficient size for 105 the inlet and outlet water pipes.

I have not attempted to show herein the 110 small details of construction which are readily understood, as, for example, it will be understood that the parts are secured together preferably by bolts, and that suitable 115 gaskets or other packing devices are provided where needed.

It will be seen that my invention secures 120 numerous advantages in practice. For example in addition to the advantageous features already referred to, the efficiency of the condenser is increased by the short and simple passages formed directly in the concrete and through which the steam flows 125 much more readily than through the passages of irregular shape made in cast iron, and the cost is greatly decreased as compared with condensers having the usual enormously heavy and expensive iron shells.

Any means for condensing the steam in the 130

- chamber formed in the foundation may be used, within the broader features of the invention, although the invention is of especial value in connection with surface condensers.
- 5 For example instead of surface condensation, condensation by a jet or jets of water may be resorted to, and generally, it is to be understood that the embodiment illustrated is intended only for affording a clear understanding of my invention which may be embodied in other forms than as shown so long as they are included within the scope of my claims by which my invention is defined.
- 10 15 Having thus described my invention, I claim:
1. A combined engine and condenser therefore, the condenser shell and engine foundation of concrete or other non-metallic material being combined for transmission of the heat expansion of the condenser shell through the foundation.
  2. A combined engine and foundation therefore, the foundation consisting of concrete or other non-metallic material and forming the shell of the condenser for the engine.
  3. An engine foundation cored out in its interior to form a condensing chamber connecting with the exhaust steam outlet of the engine, rings embedded in the foundation at the ends of the cored out chamber and provided with heads and tube plates to form condensing water boxes, and pipes connecting with the water boxes and mounted in the tube plates.
  4. An engine foundation of concrete or other non-metallic material having a condensing chamber formed directly therein and connecting with the engine exhaust, and means for circulating water through said chamber to condense the exhaust steam.
  5. An engine foundation having a condensing chamber formed directly therein and an inlet passage leading thereto, an engine on said foundation and having a flexible connection between its exhaust outlet and said inlet passage, and means for circulating water through the chamber to condense the exhaust steam.
  6. The combination with a turbine or other steam engine, of a surface condenser for the exhaust steam having its condensing chamber located below the engine and connecting directly with the engine exhaust and having its shell formed by the material of the foundation.
  7. The combination with a turbine or other steam engine and its foundation of concrete or like material, of a surface condenser having its shell formed by the foundation material and connecting with the engine exhaust and water circulating passages within the shell for surface condensation of the steam.
- In testimony that I claim the foregoing, I have hereto set my hand, this 4th day of September, 1917.
- JOSEPH D. STONE.
